COOLED BLADED ROTOR

Joseph Atkinson, London, England

Application November 19, 1946, Serial No. 710,764
In Great Britain November 30, 1945

2 Claims. (Cl. 253—39.15)

1

This invention relates to the construction and manufacture of bladed elements of turbines and compressors. Whilst, as will be appreciated from the description which follows, the invention is capable of application both to the rotors and stators of such machines, and the expression "bladed element" is accordingly intended to include both rotors and stators, the invention offers probably its maximum utility and advantage when used in relation to turbine rotors, and more particularly rotors of combustion turbines, the requirements of which it was, in fact, designed to meet.

It is usual practice for the rotor of a combustion or other turbine to be made from one or more substantial one-piece forgings or similar bodies, but this method of manufacture has a number of disadvantages, including the fact that a one-piece rotor element is expensive in first cost and that a local flaw may involve total scrapping of the element, possibly only after considerable expense has been incurred in preliminary machining operations. In addition a one-piece element is liable to certain mechanical limitations, including non-uniformity of structure and directional sensitivity to operating stresses, whilst its material may be of relatively low tensile strength and subject to loss of elasticity under the high duty conditions of temperature and stress involved, resulting in a tendency of the rotor to growth during use. One-piece rotor elements of the conventional type also involve expensive machining processes, since every finished part has to be machined from the solid, and thus do not lend themselves to mass production. Similarly, due to machining difficulties, they do not lend themselves readily to the provision of internal cooling passages.

It is an object of the present invention to eliminate or mitigate some or all of these disadvantages.

The invention is based on the conception of employing a laminar construction in the manufacture of the bladed elements of turbines and compressors, especially the rotors of combustion turbines, and in one of its aspects provides such an element which comprises a multiplicity of metal laminae held together as a pack having separately fabricated blading mounted thereon.

According further to the invention a blade carrier element for use in the construction of a bladed element as just defined comprises a multiplicity of metal laminae held together as a pack and having formations which are mutually complementary so as to provide seatings for blades to be mounted thereon.

In order to obtain the maximum advantage from the invention, particularly in eliminating or minimising the effect of local flaws in the blade carrier element and in facilitating mass production, the laminae are made of thin sheet metal which, if the element is a rotor for a combustion turbine, is preferably of a heat-resisting alloy. The expression "sheet metal"

used herein is intended to indicate metal which is sufficiently thin to be susceptible of local shaping by pressing, stamping or similar operations.

According to a further important practical feature of the invention, the sheet material used for the rotor of a combustion turbine is of a kind which has had its mechanical properties improved by a cold rolling or other pressure-working process; thus, for example, the sheets may be made of an austenitic heat-resisting alloy, a characteristic of which is that after cold rolling it less readily loses its elasticity at high temperatures and that its tensile strength is improved.

The technique of using thin sheet material lends itself well to the cheap formation of blade seatings by, in accordance with another feature of the invention, suitably stamping out portions of the peripheries of the individual laminae according to the form of seat desired, but if necessary these seatings may be finished by machining operations after the laminae have been assembled to form a carrier element. Various examples of seating forms will be given below; preferably, however, the anchorages provided for the blades are such as to distribute among the laminae the centrifugal stresses transmitted from the blades. For a similar purpose the laminae may be held together by bolts or the like passing completely therethrough so as to ensure reasonable stress distribution as between the individual laminae.

In another aspect of the invention a bladed (or a blade carrier) element of a turbine or compressor comprises a multiplicity of metal laminae held together as a pack, and a space is afforded between adjacent laminae to provide a passage for the circulation of a cooling medium, which will normally be air. Preferably this cooling passage is afforded by the co-operation of complementary formations of adjacent laminae, the latter, for example, having apertures arranged in overlapping register so as to form a continuous passage following a desired path without unduly weakening any one lamina. Alternatively, the spacing of laminae between which the passage is required may be obtained by ribbing or otherwise deforming one or more laminae.

In order that the invention may be clearly understood and readily carried into effect it will now be more fully described with reference to the examples of construction illustrated in the accompanying drawings, from which further features will appear, and in which:

Figure 1 is a partly sectional side elevation of a simple form of rotor formed by a laminated pack in accordance with the invention;

Figure 2a is a fragmentary face view of the rotor illustrated in Figure 1, illustrating one form of root seating;

Figure 2b is a fragmentary face view of the rotor of Figure 1, illustrating another form of rotor seating;

Figure 3 is a fragmentary sectional side ele-

vation of a rotor with a blade in position in an axially extending seating and showing one arrangement for preventing axial displacement of the blades;

Figures 4 and 5 are respectively a fragmentary sectional side view and face view of a rotor having a blade mounted in an axially extending seat but having an alternative arrangement for preventing axial displacement of the blades;

Figure 6 is another fragmentary sectional side view illustrating an alternative form of blade root mounting;

Figure 7 is a detail view illustrating a possible method of attaching a balance weight to a rotor;

Figures 8(a), (b) and (c) are views illustrating in plan, rear elevation, and transverse section on line C—C on Figure 8b a form of hollow sheet metal blade suitable for use with a rotor according to the invention, whilst Figures 8(d) and (e) illustrate a filler block for use in fixing such a blade;

Figures 9 and 10 are respectively a fragmentary sectional side view and face view of a rotor illustrating one method of forming cooling passages therein, with entry to the passages from the face of the rotor;

Figures 11(a), (b) and (c) illustrate alternative ways of forming internal cooling passages in a rotor;

Figure 12 is a face view of a rotor indicating three alternative ways of arranging the cooling passages by the methods illustrated in Figure 11;

Figure 13 is a part sectional side view showing an arrangement for introducing cooling air at the hub of such a rotor;

Figure 14 illustrates in axial section part of an axial flow compressor having the invention applied thereto both in the rotor and stator construction, alternative methods of blade mounting being shown, which are also illustrated in front elevation in Figures 15(a), (b) and (c).

Figures 16 and 17 are detail views illustrating alternative forms of root mounting that might be employed.

The general conception on which the invention is based is illustrated in Figure 1, which shows a turbine rotor, suitable for use in a highly stressed combustion turbine assembly, comprising a pack of sheet metal laminae 1 secured by bolts 2 to the flange of a shaft 3, the bolts 2 passing through all the laminae so that each sustains a share of the radial stress in operation. Preferably the laminae are thin sheets of a heat-resisting alloy which has had its tensile strength and elastic properties improved by a cold rolling process, a suitable alloy for the purpose being an austenitic steel alloy containing 18% chromium and 8% nickel stabilised with titanium.

This construction lends itself to a variety of root mountings for the blades; for example as illustrated in Figure 2a, and in Figure 3, a root 4 may be of the "fir tree" type commonly used in combustion turbines, this type of root and its seating being characterised by being tapered in the radially inward direction and having its sides serrated after the fashion of a buttress thread with the straight faces on the radial inner sides. This form of blade mounting has proved highly satisfactory in association with one-piece rotors, and the use of sheet material lends itself to the construction of a suitable seating therefor by simple stamping operations instead of the usual cutting and broaching from the solid, although broaching may still be used as a finishing process. In this construction axial displacement of the

blades after assembly may be prevented either by peening over the ends of the blade roots or (see Figure 3) by providing outside laminae 5 which are not notched and thus extend across the ends of the blade root faces, or again (see Figures 4 and 5) by displacing a notched lamina 6 peripherally in relation to the remainder of the laminae 1 before securing the rotor finally, so as to enter a groove in the blade root.

In place of the fir tree type of root fastening, the sides of a root and seating may have complementary semicircular grooves as indicated in respect of the root 7 in Figure 2b, the blade being retained against radial displacement by pins 8 fitting the holes thus formed, and against axial displacement by peening of the pins 8.

It will be appreciated that in each of the constructions just described the centrifugal load due to the blades will be distributed over all the laminae.

As an alternative to axially extending root mountings, adjacent laminae 1 may be of different radial dimensions as illustrated in Figure 6 so as to form peripheral channels at the rim of the rotor, and the blade roots have corresponding tongues 9 lying in the peripheral direction, the blades being locked in position by pins or dowels 10 passing through aligned holes in the tongues 9 and laminae 1 and peened over for axial retention, the arrangement thus being such that the securing pins 10 are in shear at several points along their length. With this arrangement as shown the laminae of smaller radius do not assist at their peripheries in sustaining the radial load but they can be enabled to do so by pinning the laminae together. Alternatively the laminae of smaller diameter can be left unstressed, in which case they act merely as spacers and can be made of inferior material to the larger laminae. There may, of course, be several of the latter grouped together as shown at the right hand side of the figure.

In order to cool the blades and, if necessary, the rotor itself, the latter may be formed with coolant passages 11 in the manner indicated in Figures 9 and 10, in which successive laminae 1 are pierced with holes in such a way that the holes in successive laminae overlap and together form continuous passages 11 extending from a radially inner point on the rotor to the blade root seatings. It will be noted that in this instance the passages 11 are arranged to emerge at one face of the rotor and the outermost lamina at that point is deformed to provide a lip 12 which will act as a scoop for entraining air into the passages. It will also be noted that although no one lamina is unduly weakened by perforations it is possible to obtain a distribution of coolant passages supplying every blade root.

In the alternative suggested cooling arrangement illustrated in Figures 11 to 13 it is proposed to deform individual laminae 1 so as to produce a spacing between them at desired points. For example, as illustrated in Figure 11(a), successive laminae have interengaging combined grooves and ribs 13 formed therein which result in a spacing of adjacent laminae, whilst in Figure 11(b), only ribs 14 are employed and in Figure 11(c) alternate plane and grooved laminae 1, 15 are provided. The deformations of the various types suggested may be arranged, for example, in any of the three ways indicated in Figure 12, that is, radially as at 16, annularly as at 17, or spirally as at 18, in order to provide continuous passages from some radially inner point of the rotor to

the periphery. In the example illustrated in Figures 12 and 13 it is assumed that the air is to be supplied from a hollow shaft 3 (see Figure 13) through appropriate ports communicating with an inner space 19 at the centre of the rotor.

A laminar construction of blade carrier element in accordance with the invention, particularly a rotor with cooling passages as in Figures 9 to 13, may be advantageously combined with a hollow sheet metal blade, an example of which is illustrated in Figure 8, in which a root 33 of corrugated form is employed, being secured in a correspondingly shaped seating by the insertion of an internal filler block 34. The latter has passages at 35 to conduct cooling air emerging from the rotor into the body 36 of the blade, which is open at its trailing edge and radially outer end for the escape of the cooling air into the working fluid flow.

A method of attaching rotor balance weights which makes use of the characteristics of laminar construction in accordance with the invention is illustrated in Figure 7, in which the weight is in the form of a headed stud 31 accommodated by perforating successive laminae 1 and retained by its head 32 being "buried" as shown. There might be several of these studs 31 annularly arranged on the rotor, and to assist balance adjustment each might be tapped to receive grub screws such as 31a of different weights, or bored to receive other forms of balance weight. Balancing might also be achieved by the provision of a bead 37 (Figure 3) from which material can be ground as required.

Although the drawings illustrate a simple form of rotor built up from plane laminae, it will be understood that some of these may be dished or otherwise centrifugally unbalanced in order to enable the centrifugal load to be utilised to maintain stability in the axial direction by reason of its straightening effect on the laminae.

In applying the invention to stator elements, blade carrier rings 20, as illustrated in Figure 14, may be formed each from a pack of thin laminae providing at the inner periphery of the ring suitable blade retaining formations, the individual rings 20 being supported between spacing rings 22 and the whole secured to form a rigid unit which may be mounted in an outer casing 23 or not as desired. It would be possible to construct the entire stator element as a pack or series of packs of thin sheets, but in its relation to stator elements the principal advantage offered by the invention is in adaptability to mass production, and this advantage is largely achieved if the laminar construction is confined to the blade supporting parts proper of the stator.

As indicated at 24 in Figures 14 and 15(a), the blade seatings might be formed by a simple tapered recess in all except the two outermost laminae of a ring, the blade being secured by a dowel 25. Alternatively, as at 26 (Figures 14 and 15(b)), where the blade seating is again a simple tapered recess, the outermost laminae 28 are of reduced radial depth to make room for retaining rings 20a which engage axially extending projections 27 on the roots; or again the "fir tree" type of fixing already described may be employed as at 28 (Figures 14 and 15(c)).

In the construction illustrated in Figure 14 the compressor rotor also employs the laminar construction, but in this case again the laminar packs are used only for those parts of the rotor actually required to support blades, the individual packs forming rings 29 separated by spacers 30.

In any of the cases described in the foregoing which employ axially directed blade seatings, the seating could be skewed in the manner indicated in Figure 16(b), this formation being attained quite simply by relative peripheral displacement of adjacent laminae 1 and, if necessary, machining the inner faces of the seatings to remove the small steps thus produced. A further alternative form of seating, suitable for rotor or stator elements, is illustrated in Figure 17, and is of dovetail form afforded by matching recesses 37 in successive laminae 1.

If difficulty should be experienced in achieving acceptably close limits for the axial dimension of a blade carrier element with a laminar construction in accordance with the invention, without recourse to special finishing of the surfaces of individual laminae, such difficulty may be met by using laminae of differing standard thicknesses as illustrated in Figure 6 so that by appropriate combinations of laminae the correct thickness may be obtained.

I claim:

1. A bladed rotor for an axial flow gas turbine operating at high temperatures comprising a rotor body composed of a plurality of flat metal discs, means to hold the discs together in mutually supporting relation as a pack, some of said discs having a plurality of circumferentially spaced apertures therethrough extending for only a part of the radius and only partly overlapping like apertures in adjacent discs to define a coolant passageway extending between laminae from a point adjacent the axis of the pack to its margin, blades, and means affixing said blades adjacent the marginal termini of said passageways.

2. A bladed rotor as claimed in claim 1 where-in the face of the rotor is provided with a scoop-like protrusion for entraining air into said coolant passageway at a point adjacent the axis of the pack.

JOSEPH ATKINSON.
